Garrison Smith & Henry Brown, of Philadelphia Pa.
Assignors to J. B. Abbott & A. Lawrence of same place.
Letters Patent No. 1118. Dated July 5. 1859.

The schedule referred to in these Letters Patent and making part of the same.

To all whom it may concern:

Be it known, that we Garrison Smith & Henry Brown of the City and County of Philadelphia, and State of Pennsylvania, have produced a new and original Stove Design, and we do hereby declare that the following is a full clear and exact description of the same; reference being had to the annexed drawing forming part of this Specification, which represents a Prospective view of Base, Top, Feet and Door frame.

This is a design for a gas burning cylinder stove, the ornamental castings of which consist of Base, Top, Feet and Door frame.

The base is of the form shown in the drawing, the edge of the lower plate A is ornamented in bas-relief by flowers a, and upon the rising portion of the base are the figures b and c the latter above and between the figures b. The ash pit plate B, has the foliage ornament d on each side of the circular draft opening C: the design configuration and arrangement of the several ornaments being as shown in the drawing. The foot E, has a central egg & with sweep terminating in a pawl as shown in the drawing. The top of the stove is circular and rises dome like its edge having a wavy ornament g, within which is a band ornamented in bas-relief by foliage i. The whole is surrounded by an open cast water basin cover & with handle h the whole having the configuration shown in the drawing.

The door frame is in form as shown in the drawing having around its edge sweeping foliage j, and below the door foliage m, on each side of slide s. The door bears the wavy ornament n, the whole design being as set forth in the annexed drawing.

We claim the design and configuration of the ornamental castings as above described and set forth in the annexed drawing.

In testimony whereof we have hereunto signed our names before two subscribing witnesses.

Witnesses,
